UNITED STATES PATENT OFFICE

ION V. K. HOTT, OF DAYTON, OHIO, ASSIGNOR TO THE JOYCE-CRIDLAND COMPANY, OF DAYTON, OHIO, A CORPORATION OF OHIO

LIFTING JACK

Application filed September 18, 1924. Serial No. 738,555.

This invention relates to lifting jacks and more particularly to lifting jacks of what is known as the self-lowering type, in which the load is allowed to move downwardly under its own weight but this lowering movement is regulated by suitable controlling apparatus.

One object of the invention is to provide an improved self-lowering jack in which the lowering of the load may be positively controlled.

A further object of the invention is to provide a self-lowering jack which may be power operated either to raise the load or to lower the same; and which may also be operated by hand either to raise the load or to permit the same to be lowered.

A further object of the invention is to provide such a jack with an improved retarding device for controlling the downward movement of the load, which will be of such a character that it will not resist the operation of the mechanism to elevate the load.

Other objects of the invention will appear as the mechanism is described in detail.

In the accompanying drawings Fig. 1 is a side elevation of a jack embodying my invention, showing the motor attached thereto; Fig. 2 is a vertical sectional view taken on the line 2—2 of Fig. 5; Fig. 3 is a transverse sectional view taken on the line 3—3 of Fig. 2; Fig. 4 is a section taken on the line 4—4 of Fig. 3; Fig. 5 is a section taken on the line 5—5 of Fig. 1; and Fig. 6 is a section taken on the line 6—6 of Fig. 4.

In these drawings I have illustrated one embodiment of my invention and have shown the same as applied to a screw operated jack in which the screw is held against vertical movement, but it will be understood that the invention may be applied to jacks of various kinds and may take various forms.

In that particular embodiment here shown the jack comprises a base 1 upon which is mounted an upwardly extending housing or hollow standard 2 in which is slidably mounted a ram 3 having at its upper end a load engaging member or cap 4. This ram is held against rotation in the standard by means of a key 5 which extends into a vertical slot

6 in the outer surface of the ram. The ram is provided near its lower end with a nut 7 which is held against rotation therein and, in the present instance, is provided on its opposite sides with lugs 8 which extend into slots 9 in the lower portion of the ram. Threaded in the nut 7 is a lifting screw 10 which is rotatably mounted on the base 1. The pitch of the screw is such that when unrestrained the weight of a load on the ram 3 will cause the nut to travel downwardly on the screw and thus lower the load. A spring pressed dog 11 mounted in the upper portion of the standard 2 is arranged to enter a notch 12 in the lower portion of the ram to check the upward movement thereof. Any suitable means may be provided for actuating the screw to elevate the load and, as here shown, I have rigidly secured to the lower or stem portion of the screw a worm wheel 13. In the present construction this worm wheel has mounted on the lower side thereof a bearing plate 14 having a ball race opposed to a similar ball race in a bearing plate 15 mounted on the base 1, and bearing balls 16 are mounted in these ball races to facilitate the rotation of the screw, it being noted that the stem of the screw is journaled in a bearing formed in the bearing plate 15. The worm wheel 13 meshes with a worm 17, the shaft 18 of which is journaled in bearings 19 and 20 formed in a laterally extending portion of the housing forming a part of the base 1. The pitch of this worm is such that it may be rotated by the worm wheel when the latter is actuated by the downward movement of the load.

The worm 17 is connected with suitable driving mechanism and with suitable retarding devices which may either regulate or entirely prevent the rotation of the worm by the downward movement of the load. In the present arrangement the retarding devices are in part interposed between the worm and the driving mechanism for elevating the load. The retarding devices consist in part of a worm wheel 21 which is connected with the shaft of the worm 17 and which meshes with a worm 22 on a vertical shaft 23 journaled in bearings 24 and 25 in a housing 26 rigidly secured to the base. The pitch of the worm

55

60

65

70

75

80

85

90

95

100

22 may be such as to completely lock the worm 17 against rotation or it may be such that it may be rotated by the worm wheel 21 when the latter is rotated by the downward movement of the load. The worm 22 is connected with the driving mechanism and the worm wheel 21 is connected with the shaft of the worm 17 in such a manner that the rotation of the worm wheel 21 by the worm 22 will 5 cause the worm 17 to be rotated in a direction to elevate the load, and when the worm 17 is rotated by the downward movement of the load this movement will be transmitted to the worm wheel 21, and the connection is 10 preferably in the form of a one-way clutch which will permit the worm 17 to be rotated in a direction to elevate the load independently of the worm wheel 21, as by means of a manually operated device, such as shown in 15 Fig. 3. As there shown, the shaft 18 of the worm 17 extends beyond the bearing 19 and has rigidly secured thereto a ratchet wheel 27 with which cooperates a pawl carried by a pawl carrier 28 journaled on the shaft and 20 provided with a lever socket 29 adapted to receive a lever by means of which the pawl and ratchet mechanism may be actuated to 25 rotate the shaft and the worm 17. The one-way clutch may take various forms but I have 30 here shown it as comprising a clutch member 30 rigidly secured to the shaft 18 between the worm wheel 21 and the bearing 20 and provided on its outer face with an annular 35 series of ratchet teeth 31. The worm wheel 21 is provided in its inner face with an annular series of recesses 32 in each of which is 40 slidably mounted a plunger or pawl 33 which is pressed inwardly into engagement with the ratchet teeth 31 by a spring 34, the arrangement on the ratchet teeth and the pawls 45 being such that when the worm 17 is rotated manually to elevate the load the ratchet teeth will ride over the pawls, thus permitting the worm to rotate relatively to the worm wheel, 50 but when the worm 17 is rotated by the downward movement of the load the ratchet teeth will pick up the pawls and cause the worm wheel 21 to rotate with the worm 17.

The retarding device further consists of a 55 brake or friction controlled device arranged to resist the movement of the worm 22 by the worm wheel 21. In the present construction this brake is of a multiple disk type and comprises a series of friction disks 35 mounted about the vertical shaft 23 and held against rotation relatively thereto by projections 36 formed on the disks and entering a vertical slot in the shaft. Arranged alternately with the disks 35 on the shaft 23 are a series of 60 corresponding disks 37 which also extend about the shaft but are disconnected therefrom and are held against rotation by means of projections 38 extending into a vertical groove in the inner face of the housing 26 in which the brake is mounted. When the worm

wheel 21 is rotated by the downward movement of the load the teeth thereof will act on the spiral of the worm 22 with a downward thrust and will thus cause the friction disks to be pressed into firm frictional engagement 70 one with the other so that the brake will function to resist the rotation of the worm 22, but when the worm 22 is rotated to actuate the worm wheel and thus permit the downward movement of the load the action of the spiral worm on the teeth of the worm wheel will tend to lift the worm and the shaft 23 and thus relieve the friction on the disks and permit the worm to turn freely. 75

The driving mechanism for operating the actuating means for the lifting screw may take various forms and, as here shown, it consists of a gear 39 connected with the vertical shaft 23 and meshing with a pinion 40 mounted on a shaft 41 and having connected therewith a second gear 42 which in turn meshes with a pinion 43 secured to a vertical shaft 44, the shaft 41 and 44 being journaled in suitable bearings in a housing 45 which encloses the gear train. Suitable means are provided for connecting with the gear train a portable motor whereby the driving mechanism may, when desired, be power operated. In the device here shown the shaft 44 has its upper end projecting above the housing 45, as shown at 46, and this projecting end of the shaft is squared or non-circular in shape and adapted to enter a socket 47, on the lower end of the shaft of a motor 48, whereby this motor may be quickly and easily connected with or disconnected from the gear train by merely placing the socket in engagement with or removing the same from the end of the shaft 44. If desired, the standard 2 may be provided with a yoke or U-shaped bracket 49 arranged to receive one of the horizontal handles 50 of the motor and to support the same in an upright position on the shaft 44. It will be understood that the motor 48 may 100 be of any suitable character but it is preferably either an electric motor or an air driven motor. 105

The gear train or driving mechanism is 110 preferably connected with the vertical shaft 23 in such a manner that when it is operated to elevate the load it will impart a slight upward movement to the shaft 23 and thus disengage the friction disks and release the brake so that the latter will not resist the 115 operation of the shaft. To this end the shaft 23 is so mounted in its bearings that it may have a slight vertical movement and the gear 39 is rigidly secured to a hub or sleeve 51 which is mounted about the shaft 120 and is so connected therewith that the rotation of the gear 39 in one direction will impart an upward movement to the shaft, this being preferably accomplished by providing the hub with an inclined slot 52 into which 125

extends a pin 53 mounted in the shaft, the arrangement of the slot being such that when the gear is rotated in a forward direction the lower wall of the slot will engage the pin and elevate the shaft. The hub or sleeve 51 is preferably supported on bearing balls 54 which are seated in a ball race formed in the upper end of the bearing 25. It will be apparent therefore that when the motor is operated in a direction to elevate the load the shaft 23 will first be elevated slightly to release the brake and the worm 22 will then rotate the worm wheel 21 and this movement will be transmitted through the worm 17 and worm wheel 13 to the elevating screw. When the motor is operated in a reverse direction the worm 22 will drive the worm wheel 21 in a reverse direction which will permit the worm 17 to be rotated by the downward movement of the load, thereby permitting the load to be lowered under its own weight. It will be understood that the driving mechanism or driving gears may be of any suitable character and number but inasmuch as the present device contemplates the use of a relatively high speed motor I have provided a more or less extended train of reducing gearing so that the speed of the motor may be properly reduced before it reaches the worm 22.

As has been stated the worm 22 may be rotated in a direction to permit the load to be lowered under its own weight either by the action of the motor or through suitable manually operated devices. The manually operated devices may take any suitable form. In the present instance, I have secured to the upper end of the vertical shaft 23 a beveled pinion 55 which is preferably sonnected with the shaft by means of a pin 56 extending through a transverse slot 57 in the shaft so that the latter can have a limited vertical movement with relation to the pinion. Meshing with the pinion 55 is a second beveled pinion 58 which is rotatably mounted in a suitable bearing 59 in a housing 60 which encloses the gears. Means are provided for rotating the beveled gears to actuate the shaft 23 but this rotating means is normally disconnected from the gears so that the latter may rotate freely when the shaft is driven by the motor. Preferably an actuating shaft 61 is mounted in bearings 62 and 63 in housing 60 for both rotatory and axial movement and extends loosely through the beveled gear 58 so that this gear may rotate thereon. The shaft is provided with a projection or pin 64 adapted to enter a recess 65 in the hub of the gear 58 when the shaft is forced inwardly and thereby connect the shaft with the gear to cause the latter to rotate therewith, a crank 66 being secured to the outer end of the shaft for this purpose. A spring 67 acts on the shaft 61 to hold the same normally in its outermost po-

sition in which it will be disconnected from the gear.

While I have shown and described one embodiment of my invention I wish it to be understood that I do not desire to be limited to the details thereof as various modifications may appear to a person skilled in the art.

Having now fully described my invention, what I claim as new and desire to secure by Letters Patent, is:

1. In a lifting jack, a base, a lifting screw, supported by said base, means for actuating said screw, said actuating means being of such a character that the load on said lifting screw may move downwardly under its own weight, means for retarding said downward movement of the load, and a main driving mechanism for said lifting screw, said driving mechanism operable in one direction to operate the actuating means to cause the lifting screw to elevate the load thereon and operable in the other direction to operate said retarding means to permit said downward movement of the load.

2. In a lifting jack, a base, a lifting screw supported by said base, means for actuating said screw, said actuating means being of such a character that the load on said lifting screw may move downwardly under its own weight, means for retarding said downward movement of the load, driving mechanism operable in one direction to operate the actuating means to cause the lifting screw to elevate the load thereon and operable in the other direction to operate said retarding means to permit said downward movement of the load, and means for detachably connecting a motor with said reversible driving mechanism.

3. In a lifting jack, a base, a lifting screw, supported by said base, means for actuating said screw, said actuating means being of such a character that the load on said lifting screw may move downwardly under its own weight, means for retarding said downward movement of the load, and driving mechanism comprising reducing gearing operable in one direction to operate the actuating means to cause said lifting screw to elevate the load thereon and operable in another direction to operate said retarding means to permit said downward movement of the load, and means for detachably connecting a motor with said reducing gearing.

4. In a lifting jack, a base, a lifting screw supported by said base, means for actuating said screw, said actuating means being of such a character that the load on the lifting screw may move downwardly under its own weight, means including a brake for retarding said downward movement of the load, and a main driving mechanism for said lifting screw, said driving mechanism operable in one direction to release said brake and

operate the actuating means to cause said lifting screw to elevate the load thereon and operable in another direction to operate said retarding means to permit the downward movement of the load.

5. In a lifting jack, a base, a lifting screw supported by said base, means for actuating said screw, said actuating means being of such a character that the load on said lifting screw may move downwardly under its own weight, means including a brake for retarding said downward movement of the load, driving mechanism for the actuating means for the lifting screw, and means operable by said driving mechanism to release said brake when said driving mechanism is operated in either direction.

6. In a lifting jack, a base, a lifting screw supported by said base, means for actuating said screw, said actuating means being of such a character that the load on said lifting screw will move downwardly under its own weight, a worm wheel connected with said actuating means, a worm meshing with said worm wheel and adapted to rotate said worm wheel, to cause the load on said screw to be elevated, and to be rotated by said worm wheel, a friction device connected with said worm and so arranged that the friction thereon will be relieved when said worm is rotated to actuate said worm wheel, and a main driving mechanism for said lifting screw connected with said worm.

7. In a lifting jack, a base, a lifting screw supported by said base, means for actuating said screw, said actuating means being of such a character that the load on said lifting screw will move downwardly under its own weight, a worm wheel connected with said actuating means, a worm meshing with said worm wheel and adapted to rotate said worm wheel, to cause the load on said screw to be elevated, and to be rotated by said worm wheel, a friction device connected with said worm and so arranged that the friction thereon will be relieved when said worm is rotated to actuate said worm wheel, driving mechanism for said worm, and means actuated by said driving mechanism for relieving the friction on said friction device.

8. In a lifting jack, a base, a lifting screw supported by said base, means for actuating said screw, said actuating means being of such a character that the load on said lifting screw will move downwardly under its own weight, a worm wheel connected with said actuating means, a worm meshing with said worm wheel and adapted to rotate said worm wheel, to cause the load on said screw to be elevated, and to be rotated by said worm wheel, a friction device connected with said worm, driving mechanism for rotating said worm and causing the load to be elevated, and means actuated by said driving mechanism

to relieve the friction on said friction device.

9. In a lifting jack, a base, a lifting screw supported by said base, means for actuating said screw, said actuating means being of such a character that the load on said lifting screw will move downwardly under its own weight, a worm wheel connected with said actuating means, a shaft capable of axial movement, a worm carried by said shaft and meshing with said worm wheel and adapted to be rotated thereby when said load moves downwardly, a multiple disk brake connected with said shaft, a main driving mechanism for rotating said shaft in one direction to cause the load to be elevated and in a reverse direction to permit the load to be lowered, and means controlled by the rotation of said shaft for imparting axial movement to said shaft when it is rotated in the first mentioned direction.

10. In a lifting jack, a base, a lifting screw supported by said base, means for actuating said screw, said actuating means being of such a character that the load on said lifting screw will move downwardly under its own weight, a worm wheel connected with said actuating means, a shaft capable of axial movement, a worm carried by said shaft and meshing with said worm wheel and adapted to be rotated thereby when said load moves downwardly, a multiple disk brake connected with said shaft, means for rotating said shaft in one direction to cause the load to be elevated and in a reverse direction to permit the load to be lowered, said multiple disk brake being so arranged that the action of said worm and said worm wheel, when the worm is rotated in the last mentioned direction, will tend to separate the disks of said brake.

11. In a lifting jack, a base, a lifting screw supported by said base, means for actuating said screw, said actuating means being of such a character that the load on said lifting screw may move downwardly under its own weight, a worm wheel connected with said actuating means, a shaft capable of axial movement, a worm carried by said shaft and meshing with said worm wheel and adapted to be rotated thereby when said load moves downwardly, gearing connected with said shaft for rotating the same in either direction, means for actuating said gearing, and means controlled by said gearing for imparting axial movement to said shaft to release said brake when said gearing is actuated in either direction.

12. In a lifting jack, a base, a lifting screw supported by said base, means for actuating said screw, said actuating means being of such a character that the load on said lifting screw will move downwardly under its own weight, a worm wheel connected with said actuating means, a shaft capable of axial movement, a brake controlled by the axial movement of said shaft, a worm carried by

5 said shaft and meshing with said worm wheel and adapted to be rotated thereby when said load moves downwardly, and a main driving mechanism for rotating said shaft and for imparting axial movement thereto to release said brake.

13. In a lifting jack, a base, a lifting screw supported by said base, means for actuating said screw, said actuating means being of such a character that the load on said lifting screw will move downwardly under its own weight, a worm wheel connected with said actuating means, a shaft capable of axial movement, a worm carried by said shaft and meshing with said worm wheel and adapted to be rotated thereby when said load moves downwardly, a gear for rotating said shaft, a connection between said gear and said shaft to cause the rotation of said gear to impart axial movement to said shaft, and means for actuating said gear.

14. In a lifting jack, a base, a lifting screw supported by said base, means for actuating said screw, said actuating means being of such a character that the load on said lifting screw may move downwardly under its own weight, a worm wheel connected with said actuating means, a shaft capable of axial movement, a worm carried by said shaft and meshing with said worm wheel, and adapted to be rotated thereby when said load moves downwardly, a sleeve mounted on said shaft having an inclined slot, a gear rigidly secured to said sleeve, means for rotating said gear, and a pin on said shaft extending into said slot.

15. In a lifting jack, a base, a lifting screw supported by said base, means for actuating said lifting screw, said actuating means being of such a character that the load on said lifting screw may move downwardly under its own weight, a worm wheel connected with said actuating means, a shaft, a worm carried by said shaft and meshing with said worm wheel, power operated means to rotate said worm in a direction to cause said load to be elevated, and manually operated means to rotate said worm in a direction to permit said load to be lowered.

16. In a lifting jack, a base, a lifting screw supported by said base, means for actuating said lifting screw, said actuating means being of such a character that the load on said lifting screw may move downwardly under its own weight, a worm wheel connected with said actuating means, a shaft, a worm carried by said shaft and meshing with said worm wheel, a train of gearing connected with said shaft, means for detachably connecting a motor with said train of gearing, and manually operated means connected with said shaft for rotating the same independently of said motor.

17. In a lifting jack, a base, a lifting screw supported by said base, means for actuating

said lifting screw, said actuating means being of such a character that the load on said lifting screw may move downwardly under its own weight, a worm wheel connected with said actuating means, a shaft, a worm carried by said shaft and meshing with said worm wheel, a train of gearing connected with said shaft, means for detachably connecting said gearing with a motor to rotate said shaft in a direction to elevate the load, other gearing connected with said shaft, and means for actuating said other gearing to rotate the shaft in a direction to permit the load to be lowered.

18. In a lifting jack, a base, a lifting screw supported by said base, means for actuating said lifting screw, said actuating means being of such a character that the load on said lifting screw may move downwardly under its own weight, a worm wheel connected with said actuating means, a shaft, a worm carried by said shaft and meshing with said worm wheel, a gear connected with said shaft, means for detachably connecting a motor with said gear, a beveled gear secured to said shaft, a second beveled gear meshing with the first mentioned beveled gear, a shaft normally disconnected from said second beveled gear but movable into and out of operative relation thereto, and means for operating said shaft.

19. In a lifting jack, a base, a lifting screw supported by said base, means for actuating said screw to elevate the load, said actuating means being of such a character that the load on said lifting screw will move downwardly under its own weight, a worm wheel, a one-way clutch connecting said worm wheel with said actuating means, a worm meshing with said worm wheel, and a main driving mechanism for rotating said worm in one direction to lift the load on said screw and in the other direction to permit the load to move downwardly under its own weight.

20. In a lifting jack, a base, a lifting screw supported by said base, means for actuating said screw to elevate the load, said actuating means being of such a character that the load on said lifting screw will move downwardly under its own weight, a worm wheel, a one-way clutch connecting said worm wheel with said actuating means, a worm meshing with said worm wheel, driving means for rotating said worm in one direction to lift the load on said screw and in the other direction to permit the load to move downwardly under its own weight, and means for detachably connecting said rotating means with a motor.

21. In a lifting jack, a base, a lifting screw supported by said base, means for actuating said screw, said actuating means being of such a character that the load on said lifting screw may move downwardly under its own weight, a worm wheel, a one-way clutch connecting said worm wheel with said actuating means, a worm meshing with said worm

wheel, power operated means for rotating said worm in either a forward direction or in a reversed direction, and manually operated means to rotate the worm in a reverse direction.

5 22. In a lifting jack, a base, a lifting screw, supported by said base, means for actuating said screw, said actuating means being of such a character that the load on said lifting screw may move downwardly under its own weight, a worm wheel, a one-way clutch connecting said worm wheel with said actuating means, a worm meshing with said worm wheel, power operated means for rotating said 10 worm in a direction to operate said actuating means, and other means for rotating said worm in a reverse direction to permit the downward movement of said load.

23. In a lifting jack, a base, a lifting screw supported by said base, a worm wheel secured to said lifting screw, a worm meshing with said worm wheel and adapted to be rotated thereby when the load moves downwardly, a second worm wheel connected with said 25 worm, a second worm meshing with said second worm wheel, manually operated means for rotating said second worm, and means for detachably connecting a motor with said second worm.

30 24. In a lifting jack, a base, a lifting screw supported by said base, a worm wheel secured to said lifting screw, a worm meshing with said worm wheel and adapted to be rotated thereby when the load moves downwardly, 35 a second worm wheel connected with said worm, a second worm meshing with said second worm wheel, a train of gearing connected with said second worm, a shaft secured to one gear of said train and having means for detachably connecting the same with a motor, 40 and a manually operated device connected with said worm.

25. In a lifting jack, a base, a lifting screw supported by said base, a worm wheel secured to said lifting screw, a worm meshing with said worm wheel and adapted to be rotated thereby when the load moves downwardly, a second worm wheel connected with said worm, a second worm meshing with said second worm wheel, a multiple disk brake connected with said second worm, said second worm being capable of axial movement to control the friction on said brake, driving mechanism for said worm, and means actuated by said driving mechanism to impart axial movement to said worm.

50 26. In a lifting jack, a base, a lifting screw supported by said base, a worm wheel secured to said lifting screw, a worm meshing with said worm wheel and adapted to be rotated thereby, manually operated means connected with said worm for rotating the same, a second worm wheel, a one-way clutch connection between said second worm wheel and said worm, a second worm meshing with said

second worm wheel, and means for rotating said second worm in one direction to cause the lifting screw to elevate the load and for rotating said second worm in the opposite direction to permit the load to be lowered.

70 27. In a lifting jack, a base, a lifting screw supported by said base, a worm wheel secured to said lifting screw, a worm meshing with said worm wheel and adapted to be rotated thereby, manually operated means connected with said worm for rotating the same, a second worm wheel, a one-way clutch connection between said second worm wheel and said worm, a shaft, a second worm carried by said shaft and meshing with said second worm wheel, a gear train connected with said shaft and having means for detachably connecting the same with a motor, and manually operated means connected with said shaft for operating the same independently of said motor.

75 28. In a lifting jack, a base, a lifting screw supported by said base, a worm wheel secured to said lifting screw, a worm meshing with said worm wheel and adapted to be rotated thereby, manually operated means connected with said worm for rotating the same, a second worm wheel, a one-way clutch connection between said second worm wheel and said worm, a shaft capable of axial movement, a second worm carried by said shaft, meshing with said second worm wheel and adapted to be rotated thereby, a plurality of friction disks secured to said shaft, other friction disks mounted independently of said shaft and interleaved between the first mentioned disks, driving gearing operatively connected with said shaft for rotating the same in either direction, and means actuated by said driving gearing for imparting axial movement to said shaft.

80 29. In a lifting jack, a base, a lifting screw supported by said base, a worm wheel secured to said lifting screw, a worm meshing with said worm wheel and adapted to be rotated thereby, manually operated means connected with said worm for rotating the same, a second worm wheel, a one-way clutch connection between said second worm wheel and said worm, a shaft capable of axial movement, a 110 second worm carried by said shaft, meshing with said second worm wheel and adapted to be rotated thereby, a plurality of friction disks secured to said shaft, other friction disks mounted independently of said shaft 100 and interleaved between the first mentioned disks, and means for rotating said shaft and said worm in either direction.

115 30. In a lifting jack, a base, a lifting screw supported by said base, a worm wheel secured to said lifting screw, a shaft, a worm secured to said shaft, meshing with said worm wheel and adapted to be rotated thereby, a manually operated device connected with said shaft for rotating said worm, a clutch mem- 125
